CLAIM

The ornamental design for a shelf divider, as shown and described.

DESCRIPTION

FIG. 1 is an isometric view of a shelf divider incorporating my new design;

FIG. 2 is a front elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The broken lines shown are for illustrative purposes only and form no part of the claimed design.
